(57) **CLAIM**

The ornamental design for a card type speaker, as shown and described.

DESCRIPTION

FIG. 1 is a perspective view of the top, front and right side of a card type speaker showing my new design;

FIG. 2 is a perspective view of the top, rear and left side thereof;

FIG. 3 is a top plan view thereof;

FIG. 4 is a front view thereof; and,

FIG. 5 is a rear view thereof.

The broken line showing on FIGS. 1-5 is for illustrative purposes only and forms no part of the claimed design.
